UNITED STATES PATENT OFFICE.

JEAN THEOBALD, OF NORTH ATTLEBOROUGH, MASSACHUSETTS, ASSIGNOR
TO THE FRANK M. WHITING & COMPANY, OF SAME PLACE.

DESIGN FOR A BACK FOR BRUSHES OR SIMILAR ARTICLES.

SPECIFICATION forming part of Design No. 29,275, dated August 30, 1898.

Application filed July 22, 1898. Serial No. 686,624. Term of patent 3½ years.

To all whom it may concern:

Be it known that I, JEAN THEOBALD, a citizen of the United States, residing at North Attleborough, in the county of Bristol, State 5 of Massachusetts, have invented and produced a new and original Design for the Back of a Brush or Similar Article, of which the following is a specification, reference being had to the drawing accompanying and forming a part of the same.

The drawing is a view of the back of a hair-brush, of which A is the handle and B the body.

The leading features of my design consist 15 in the peculiar and novel outline and configuration composed of a series of husk ornamentalations combined with elaborate foliated scroll ornaments.

More particularly described, my design is 20 as follows: Following the swelled contour of the handle A at a distance from its margin are a series of husk ornamentalations a a, each series inclosed by a marginal and interior bead b c, the inner members of which converge 25 near the handle's base and terminate in diverging scroll ornamentalations d. These retreat upwardly a distance on either side of the handle e e and form the terminal contour of the same. Immediately below the junction 30 of the brush handle and head are oppositely disposed scrolls ff, their convex portions contiguous at the axial line g, their heads terminating in foliates. Springing downwardly

from g and partially overlapping the central boss o of the handle are conventionalized leaf 35 forms jj with a triple-scroll termination. Rising upwardly from g on either side of an oblong plain ornament m and expanding to cover most of the lower brush-body are elaborate leaf ornaments k k with scroll terminations, beneath which are single husk ornaments i i. The lower center of the brush-head is an elliptical surface l, embraced by inwardly-inclined foliates n n with interior leafy branches p p. Following the outer contour of foliates n n are series of husks q q, treated as those in the handle. The crest ornamentation begins at the junction of foliates n n with a flower r and pendent leaf s. Above the flower r elaborate leafy and floral 50 foliates t t roll outwardly on either side, resting on the beads u u. Between the heads of the scrolls t t rises the crowning ornament v, consisting of converging scrolls embracing a plain boss z and flanked by husks x x. 55

Having thus described my invention, what I claim as new, and desire to secure by Letters Patent, is—

The design for a back of a brush or similar article herein shown and described. 60

In witness whereof I have hereunto set my hand.

JEAN THEOBALD.
